CLAIM

The ornamental design for an antenna, as shown and described.

DESCRIPTION

FIG. 1 is a front plan view of an antenna.

FIG. 2 is a top plan view of the antenna of FIG. 1.

FIG. 3 is a bottom plan view of the antenna of FIG. 1.

FIG. 4 is a top perspective view of the antenna of FIG. 1; and, FIG. 5 is a front plan view of an antenna within a cover in broken lines.

The broken lines are for illustration purposes only and form no part of the claimed invention.
